UNITED STATES PATENT OFFICE.

WILLIAM F. MICHAEL, OF PHILADELPHIA, PENNSYLVANIA, ASSIGNOR TO
BAILEY, BANKS & BIDDLE, OF SAME PLACE.

DESIGN FOR A SPOON.

SPECIFICATION forming part of Design No. 21,040, dated September 15, 1891.

Application filed July 9, 1891. Serial No. 398,976. Term of patent 3½ years.

To all whom it may concern:

Be it known that I, WILLIAM F. MICHAEL, a citizen of the United States, residing in the city and county of Philadelphia, State of Pennsylvania, have invented and produced a new and original Design for a Spoon, of which the following is a specification, reference being had to the accompanying drawing, forming part thereof.

10 The leading feature of my design for a spoon is the handle having the representation of the bust of a man on the tip thereof.

15 In the drawing, A designates the handle of a spoon, the same increasing in width from the bowl outward and joining at its widest end the representation of a bust B of a man. On the handle is the representation of a streamer

C, the same being apparently wound around said handle from the bust to the bowl. On the streamer is the inscription "George W. 20 Childs, Public Ledger, Philadelphia." Obviously such inscription forms no part of my design and may be omitted.

I claim—

25 A design for a spoon having a handle with the representation of the bust of a man on the tip thereof, and the representation of a streamer extending from the bust to the handle, as shown and described.

WILLIAM F. MICHAEL.
